UNITED STATES PATENT OFFICE.

ARTHUR L. JACOBS, OF BOSTON, MASSACHUSETTS, ASSIGNOR, BY MESNE ASSIGNMENTS,
TO JENNIE M. JACOBS, OF BOSTON, MASSACHUSETTS.

ELECTRIC-LAMP SOCKET.

1,013,658.

Specification of Letters Patent.

Patented Jan. 2, 1912.

Application filed May 16, 1910. Serial No. 561,611.

To all whom it may concern:

Be it known that I, ARTHUR L. JACOBS, a citizen of the United States, residing at Boston, in the county of Suffolk and State 5 of Massachusetts, have invented new and useful Improvements in Electric-Lamp Sockets, of which the following is a specification.

This invention relates to improvements in 10 electric lamp sockets, and the object is to provide a socket which shall be simple, inexpensive and durable in construction and which shall be capable of being easily and quickly assembled.

15 Another object of my invention is to provide a socket in which there shall be a double break, that is, two breaks will occur simultaneously in the electrical connections of the same polarity.

20 The object is still further to provide a socket in which the key-shaft shall be insulated thereby obviating the dangers incident to the use of a non-insulated shaft.

25 The invention consists in the novel features of construction and in the combination and arrangement of parts set forth in the following specification and particularly pointed out in the appended claims.

Referring to the drawing: Figure 1 is an 30 elevation, partly in section, of a socket embodying my invention, the usual exterior casing therefor being omitted. Fig. 2 is a plan section taken on line 2—2 of Fig. 1. Fig. 3 is a bottom plan of the socket. Fig. 35 4 is a sectional view taken on line 4—4 of Fig. 1, looking toward the right showing the position which the parts occupy when the circuit is broken. Fig. 5 is a sectional view similar to Fig. 4 except that the parts are 40 shown in the position which they occupy when the circuit is closed. Fig. 6 is a detail perspective view of the conductor which constitutes one of the lamp terminals. Fig. 45 7 is a detail perspective view of the conductor which constitutes one of the wire terminals together with its spring contact piece. Fig. 8 is a perspective view of the socket, the two insulating blocks of which are partly broken away and shown in section to show the mode of attachment of the parts.

Like numerals refer to like parts throughout the several views of the drawing.

In the drawing, 10 is the base of the 50 socket, which base comprises two blocks 11

and 12 formed of insulating material, preferably porcelain, and provided, respectively, with cavities 13 and 14 forming together a shoulder 15 for the switch mechanism. Within the shoulder 15 is located a conductor 60 16 constituting a spring having two relatively movable parts 17 and 18, the form of said spring being such as to render said parts resilient so as to be capable of considerable movement without getting a permanent set. Between the parts 17 and 18 is located a rotatable cam 19 which may be formed either of metal or of some non-conducting material, such as porcelain, preferably the latter.

70 By making the cam of insulating material, a much desired result is attained, viz, the key is insulated and consequently can, with perfect safety, be provided with a metallic thumb-piece which can have special 75 finishes like the socket casing and in this way a much more artistic appearance is given to the socket than could be effected were the key-shaft non-insulated, in which case a thumb-piece of insulating material 80 would be necessary. Moreover, even if it be desired to employ a non-conducting thumb-piece, still the insulated key-shaft is an advantage since the rubber thumb-pieces are apt to break off, leaving the bare shaft 85 which may be a source of danger because not only is the shaft itself charged, as in most sockets, but the casing will also become charged if the shaft becomes displaced and touches the casing. These disadvantages 90 are overcome by employing the non-conducting cam which causes a double break and yet does not constitute a switch-block. This feature of my improved socket is one, the advantages of which will be readily appreciated by those skilled in the art.

The cam 19 is provided with a hole 20 through which extends a key shaft 21 carrying on its outer end a thumb piece 22, said key shaft being provided with two usual 100 lateral projections 23 located in recesses 24 formed in the cam 19, said recesses being segmental in form and being of such extent as to permit a certain amount of relative rotation between the key shaft 21 and cam 105 19 in the usual and well known manner. A conductor 25 constituting a lamp terminal is provided with a horizontal portion 26 for contact with the lamp and extends vertically through a passage 27 formed in the 110

block 12 into the cavity 14 and being provided with a horizontal portion 28 extending between the abutting faces of the blocks 11 and 12, said portion 28 being provided with a spur 29 extending into a hole provided in an L-shaped spring contact piece 30 which also extends between the abutting faces of the blocks 11 and 12, said blocks being provided, respectively, with shallow recesses 31 and 32 to receive these parts. The block 11 is still further provided with a recess 33 adapted to receive the spur 29.

On the opposite side of the base is a conductor 34 shown in detail in Fig. 7, said conductor having a horizontal portion 35 located in a corresponding recess 36 provided in the block 12, said conductor being provided with an ear 37 screw-threaded to receive a screw 38 provided for the attachment 20 of one of the line wires. The conductor 34 is provided with a projection 39 extending downwardly into the cavity 14 and said conductor is also provided with a spur 40 located in a hole provided in an L-shaped 35 spring contact piece 41, a portion of which extends between the abutting faces of the blocks 11 and 12, the block 11 being provided with a recess 42 to receive such part of said contact piece. The block 11 is 30 still further provided with a recess 43 adapted to receive the spur 40.

A screw-threaded metallic shell 44 constituting one of the lamp terminals is provided with an inwardly turned flange 45 surrounding a boss 46 formed on the block 12, said flange being provided with a hole 47 through which passes a screw 48, said screw extending also through holes 49 and 50 provided in the blocks 11 and 12, respectively, and said screw terminating in and having screw-threaded engagement with a plate 51 bearing against the under side of the flange 45, said screw thus serving to rigidly connect the shell 44 and the blocks 11 45 and 12.

On the opposite sides of the boss is a conductor 52 provided with a screw-thread to receive a screw 53 for the connection of one of the line wires, said conductor extending 50 through a hole 54 formed in the block 12 and having a horizontal portion 55 extending beneath the flange 45, said horizontal portion being provided with a screw-threaded hole 56 which receives a screw 57, said screw extending through holes 58 and 59 provided in the blocks 12 and 11, respectively, and serving to rigidly connect said blocks to each other and to the shell 44.

The screws 48 and 57 constitute the sole 60 means for securing the lamp terminals, the line wire terminals and switch mechanism in place, all of the parts of the socket being first loosely assembled after which said screws are inserted, thus completing the 65 socket.

The operation of the socket is as follows: Fig. 4 shows the position which the parts occupy when the circuit is broken. The key 22 is grasped in the fingers and rotated, thereby rotating the cam 19 into the position shown in Fig. 5, said cam acting to spread the parts 17 and 18 of the spring 16 and cause the same to contact with the spring contact pieces 30 and 41, said contact pieces yielding and insuring perfect contact. If 75 now a lamp should be screwed into the shell 44 the electrical circuit would be complete, the current passing through the conductor 52, shell 44, the lamp, the conductor 25, contact piece 30, spring 16, contact piece 41 and 80 conductor 35 to the line wire. If now the switch shaft be rotated from the position shown in Fig. 5 to the position shown in Fig. 4, the cam 19 will be carried thereby and during its rotation will be given a sudden impetus by the spring parts 17 and 18 and will arrive in the position shown in Fig. 4. During this movement the spring parts 17 and 18 are simultaneously separated from the spring contact pieces 30 and 41 and thus the circuit is broken at two 85 points in the electrical connections of the same polarity.

If the cam 19 be formed of insulating material the spring 16 will, of course, constitute the sole conductor between the contact pieces 30 and 41, but if said cam be formed of metal a part of the current will, of course, flow therethrough.

Having thus described my invention, what 100 I claim and desire by Letters Patent to secure is:

1. An electric lamp socket having, in combination, a base composed of two blocks of insulating material placed face to face and provided, respectively, with cavities forming a chamber, two conductors extending between the opposed faces of said blocks and held by their engagement therewith, and a switch mechanism located in said chamber adapted to electrically connect said conductors.

2. An electric lamp socket having, in combination, a base composed of two blocks of insulating material placed face to face and provided, respectively, with cavities forming a chamber, a spring located in said chamber and held in place therein by contact with the walls thereof, said spring having two relatively movable parts, two conductors extending between the opposed faces of said blocks and held in place by their engagement therewith, and a rotatable member located in said chamber and adapted to be rotated to actuate said spring parts to make electrical connection between said conductors.

3. An electric lamp socket having, in combination, a base composed of two blocks of insulating material placed face to face,

means to secure said blocks to each other, two conductors extending between the opposed faces of said blocks and held by their engagement therewith, and a switch mechanism interengaging with said blocks and adapted to electrically connect said conductors, said mechanism being held in operative position solely by its interengagement with said blocks.

- 10 4. An electric lamp socket having, in combination, a base composed of two blocks of insulating material placed face to face and provided, respectively, with cavities forming a chamber, means to secure said blocks to each other, a switch mechanism located

in said chamber, and two conductors extending between the opposed ends of said block, said mechanism and said conductors being held in operative position solely by the engagement of said mechanism with the walls 20 of said chamber and by the engagement of said conductors with the opposed ends of said blocks.

In testimony whereof I have hereunto set my hand in presence of two subscribing witnesses.

ARTHUR L. JACOBS.
